Primary Examiner — Jae Liang
Assistant Examiner — Bryan C Gusman

(57) **CLAIM**

The ornamental design for a table with tablecloth, as shown and described.

DESCRIPTION

FIG. 1 is a front, top and right-side perspective view of a table with tablecloth showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom and left-side perspective view thereof; and,

FIG. 9 is an enlarged view, of circled portion 9, of FIG. 3, thereof.

The dot-dash broken lines depict the boundaries of the FIG. 3 and FIG. 9 enlargement that form no part of the claimed design.

1 Claim, 9 Drawing Sheets
